UNITED STATES PATENT OFFICE.

SANFORD M. McCURDY, OF ADA, OHIO.

FEEDING DEVICE FOR POULTRY.

1,410,689.

Specification of Letters Patent. Patented Mar. 28, 1922.

Application filed September 13, 1920. Serial No. 409,790.

To all whom it may concern:

Be it known that I, SANFORD M. McCURDY, a citizen of the United States, residing at Ada, in the county of Hardin and State of Ohio, have invented certain new and useful Improvements in Feeding Devices for Poultry, of which the following is a specification.

My invention relates to improvements in feeding devices, it particularly relating to a feeding device especially for poultry, although the constructions are applicable to a feeder for hogs or other animals.

One of the objects of my invention is to provide a structure embodying feed troughs which may be readily and simply adjusted as to size.

A further object of my invention is to devise a construction of the character referred to, the parts of which may be readily taken apart for cleaning purposes and as readily reassembled; the feature permitting the device to be shipped in knocked-down state and readily and quickly assembled for use.

A further object of my invention is to provide a simple arrangement whereby the feed is prevented from being splashed out of the troughs by the poultry.

A further object of my invention is to provide a feeding device of the character referred to which will be simple in construction, economical in manufacture and effective in use.

In the accompanying drawings:—

Fig. 1 is a top plan view with the cover removed.

Fig. 2 is a longitudinal section on the line 2—2 of Fig. 1.

Fig. 3 is a vertical section on the line 3—3 of Fig. 1 showing, however, the cover for the top of the structure.

Fig. 4 is an end view.

Fig. 5 is a side elevation.

Referring to the drawings, the walls and troughs of the structure are preferably constructed of sheet metal, 1 and 2 representing the respective ends which have their edges bent laterally upon themselves as indicated

at 1^a and 2^a for stiffening purposes and also for the purpose of eliminating any sharp edges. Clamped between the respective ends are side walls, each of which is formed of a downwardly inclined portion 3 and a

straight vertical portion 4, the lower edge

of the vertical portion being rolled as indicated at 5 to provide a longitudinally-extending outwardly-projecting hollow bead, the upper edges of the portions 3 of the side walls are also rolled as indicated at 6 to provide similar beads. The ends of each side wall are preferably bent laterally as indicated at 3^a and 4^a so as to provide a surface of sufficient width to make a good contact with the end. In order to clamp the side walls between the ends, a series of rods 7 are extended through the respective beads and the end walls, the respective ends of which are threaded to receive nuts 8, so that the ends and the side walls may be permanently clamped together. These end walls and side walls form a hopper for the feed which has a wide flaring mouth with a comparatively narrow straight sided lower portion open at the bottom.

Beneath the hopper thus formed are two channel-shaped troughs 9 and 10 formed of a single piece of metal, the inner edges of the troughs terminating in an apex 11 which projects into the lower portion of the hopper, being centrally-positioned between the two side walls 4. The outer edge of each of the troughs is rolled as indicated at 12 to form a hollow bead and through these beads are extended rods 13 which also extend through the respective ends 1 and 2 and are clamped thereto by nuts 14 threaded thereon. The ends of the channels are bent laterally and cut at intervals as indicated at 9^a and 10^a in Fig. 3.

Extending through the end walls in a position to lie beneath the apex portion 11 of the troughs is a rod 15 with threaded ends to receive nuts 16 and 17, the one 17 being preferably a wing nut. This rod 15 and its nuts are for the purpose of clamping the central portion of the troughs between the end walls, but when loosened by unscrewing the wing nut 17 the troughs may be readily adjusted with respect to the hopper by pressing the central portion thereof up or down, the beads pivoting upon the rods 13 and the resilient nature of the metal forming the troughs readily lending itself to the different positions assumed; one of the adjusted positions being shown in dotted lines in Fig. 3. By this means the size of the throats leading to the troughs may be adjusted to suit the different feeds and other conditions encountered.

As indicated in Fig. 3, a cover is preferably provided to close the top of the structure.

By the arrangement of the beads 5 on the lower edges of the hopper walls 4 in conjunction with the beads 12 on the outer edges of the troughs, provision is made for preventing the poultry, hogs or other animals, from scattering the feed outside of the troughs, 10 the feed tending to strike these overhanging beads and fall back into the troughs.

Further, by the employment of the connecting rods, the end walls hopper portions and troughs may be readily taken apart for 15 transportation or cleaning and as readily placed together.

Having thus described my invention, I claim:—

1. In a device of the character described, 20 a hopper open at the bottom, a trough beneath said hopper and communicating therewith, end walls for supporting said hopper from the ground, said trough co-operating with a lower edge of said hopper to form a throat, and means for clamping said trough in different positions of adjustment between and by said end walls to vary the size of said throat.

2. In a device of the character described, 30 a hopper open at the bottom, end walls for supporting said hopper from the ground, a trough located beneath and communicating with the open bottom of said hopper, said trough co-operating with a lower edge 35 of said hopper to form a throat, and means for releasably clamping said end walls to the ends of said trough to permit said trough to be adjusted to different positions to vary the size of said throat.

3. In a device of the character described, 40 a hopper open at the bottom, end walls for supporting said hopper from the ground, a pair of connected troughs beneath said hopper having their dividing line substantially midway the width thereof, said troughs cooperating with the lower edges 45 of said hopper to form throats, and means for clamping said troughs in different positions by said end walls to vary the sizes of said throats.

4. In a device of the character described, 50 a hopper open at the bottom, end walls for supporting said hopper from the ground, a pair of connected troughs beneath said hopper and communicating therewith, said troughs co-operating with the respective lower edges of said hopper to form throats, and a rod and means thereon extending 55 between said walls and beneath said troughs 60 for releasably clamping said walls to the

ends of said troughs to permit said troughs to be adjusted relatively to the lower edges of said hopper, for the purpose specified.

5. In a device of the character described, 65 a hopper open at its lower end, end walls for supporting said hopper from the ground, a pair of concave troughs beneath said hopper having their dividing line located substantially midway the width of said hopper and projecting therein, said troughs co-operating 70 with the lower edges of said hopper to form throats, and means for releasably clamping said end walls to the ends of said troughs to permit adjustment of said troughs to vary the sizes of said throats. 75

6. In a device of the character described, a hopper open at the bottom, end walls for supporting said hopper, a pair of troughs formed of resilient material beneath said hopper, rods supported by the end walls 80 upon which the outer edge of each trough is hung, and means for releasably clamping the end walls to the ends of said troughs whereby said troughs when released by the end wall may be swung to different positions of adjustment.

7. In a device of the character described, 90 a hopper open at the bottom, end walls for supporting said hopper, a pair of connected troughs beneath said hopper and communicating therewith, said troughs being formed of resilient sheet metal with the outer edge of each trough bent in the form of a hollow bead, rods supported by the end walls and extending through said hollow beads, and 95 means for releasably clamping the end walls to the ends of said troughs.

8. In a device of the character described, 100 a hopper open at its lower end, said hopper being formed of sheet metal and having the upper and lower edges of each wall thereof rolled in the form of hollow beads, a trough member beneath said hopper and communicating with the lower end thereof, said trough member being formed of sheet metal 105 and having its outer edges rolled in the form of hollow beads, end walls, and rods supported by said end walls and projected through the respective hollow beads to clamp the hopper to said end walls and form 110 pivotal supports for said trough member, and additional means for releasably clamping the trough member to said walls.

In testimony whereof, I have hereunto set my hand this 17th day of August, 1920. 115

SANFORD M. McCURDY.
